CLAIM

The ornamental design for a watch-shaped book, as shown and described.

DESCRIPTION

FIG. 1 is a perspective view of the top, front and left side of a watch-shaped book showing my new design;
FIG. 2 is a view similar to FIG. 1 with the case open;
FIG. 3 is a top plan view thereof;
FIG. 4 is a bottom plan view thereof;
FIG. 5 is a rear elevational view thereof;
FIG. 6 is a front elevational view thereof;
FIG. 7 is a left side elevational view thereof; and,
FIG. 8 is a right side elevational view thereof.
